UNITED STATES PATENT OFFICE.

HARRY C. GAMMETER, OF CLEVELAND, OHIO, ASSIGNOR, BY DIRECT AND MESNE ASSIGNMENTS, TO THE AMERICAN MULTIGRAPH COMPANY, OF CLEVELAND, OHIO, A CORPORATION OF OHIO.

DUPLICATING-MACHINE.

SPECIFICATION forming part of Letters Patent No. 722,404, dated March 10, 1903.

Application filed April 22, 1902. Serial No. 104,131. (No model.)

To all whom it may concern:

Be it known that I, HARRY C. GAMMETER, a citizen of the United States, residing at Cleveland, in the county of Cuyahoga and State of Ohio, have invented certain new and useful Improvements in Duplicating-Machines, of which the following is a specification, reference being had therein to the accompanying drawings.

10 In business it is often desirable to reproduce circular letters or similar written matter in large quantities, and my invention relates to machines for this purpose. It is especially adapted for duplicating letters so that they 15 have all the appearances of having been written upon a type-writer, with the incidental advantages.

That form of the machine to be described comprises two drums, distinguished as the 20 printing-drum and the supply-drum. The former is adapted to have type set up upon it and is operated so that their impression is taken upon a sheet of paper. The supply-drum, as its name indicates, carries the type 25 when not in actual use. These two drums are on the same axis and are so constructed that they enable the type from the supply-drum to be passed to the printing-drum, automatic mechanism being provided for this 30 purpose and for assisting in the proper distribution of the type upon the supply-drum after the operation.

The invention consists in a certain construction and combination of parts to be more 35 fully described hereinafter and definitely set forth in the claims.

In the drawings, which fully illustrate my invention, Figure 1 represents a central cross-section of the same in a vertical plane. Fig. 40 2 represents the mechanism in side elevation, a portion of the frame being broken away to more fully disclose the interior construction. Fig. 3 represents the mechanism in plan, a portion being broken away, as indicated. Fig. 45 4 is a vertical cross-section taken on the line 4 4 of Fig. 3. Fig. 5 is a cross-section taken substantially on the line 5 5 of Fig. 1, but on enlarged scale. Fig. 6 represents in section a portion of the printing-drum used in

connection with this invention. Fig. 7 represents, on an enlarged scale, a detail of a connection used in this machine. Fig. 8 is a detail elevation of certain feeding mechanism, the part in connection therewith being broken away. Fig. 9 is a plan of a keeper used in 55 every line. Fig. 10 is a detail elevation, on an enlarged scale, of the inner ends of certain feeding-racks; and Fig. 11 is a detail elevation of a rock-wheel.

Referring to the parts by numerals, 1 represents the frame, which comprises a substantially horizontal base or bed 2, provided on either side with upwardly-projecting standards 3 4, preferably formed integrally with the base. Upon these standards is mounted a 60 horizontal shaft 5, which is provided at its outer extremity with a gear 6, which is rigid therewith. Upon this horizontal shaft 5 is mounted a rotatable drum 7, which will be described more in detail hereinafter. The inner extremity of this shaft is provided with another drum 8, which is rotatably mounted and is capable of a limited sliding movement upon the shaft for a purpose which will appear.

The drum 7 comprises substantially spiders or ends 124, which are connected by a cylindrical portion or body 9. This cylindrical body is not, however, continuous, but is cut away upon its rear side, as indicated at 10. 80 Its outer face 11 is constructed substantially as indicated in Fig. 6. It is provided with longitudinal channels or ways 12, which extend from end to end and which are formed, preferably, by means of T-shaped strips 13, set 85 tightly into narrow longitudinal grooves 14 in the face of the drum. Within these channels type 15 are carried, and each type is provided with grooves 16 at either side, which receive the slightly-projecting T-heads 17 of 90 the aforesaid strips 13, wherefore they are maintained within the recess. This drum 7 is adapted to be rotated by means of a gear 18, which is rotatably carried by the aforesaid standard 3 and provided with a crank or 95 handle 19.

Spools 20 carry between them a web or band 21, which passes around the channeled face

- 9 of the drum 7 and lies over the printing-faces of the type 15, which project, as indicated, slightly above the face of the drum. The width of this band is so great that it substantially covers the printing-face of the drum. It is constructed of some suitable transfer material, such as fabric, which has absorbed ink and is similar to an ordinary type-writer ribbon.
- 10 One end of the drum is provided for a portion of its periphery (which portion corresponds substantially with the printing-face of the drum) with gear-teeth 22, which are adapted to engage with a rack 23 on the carriage 24, which is mounted horizontally in the aforesaid bed 2.

Now from the construction described it will be readily understood that when the crank 19 is turned the drum 7 will be rotated, and 20 at the same time the carriage 24 will pass beneath the drum and will slide toward the opposite end of the bed, and when the carriage passes in this manner a platen 25 on the carriage will be impressed by the projecting faces of the type carried on the face of the drum 7; but it will be remembered that the band 21, which has already been described, passes about this drum 7 and rests upon the printing-face of the type, and hence if a piece 25 of paper were placed upon the platen 25 it would be impressed by the type and written matter would be produced corresponding to that which had been set up upon the drum. This platen projects above the face of the carriage, as indicated, and is preferably made 30 of rubber of slight elasticity. In order to prevent any possibility of the teeth upon the rack 23 jamming and not coming into proper mesh with the gear-teeth 22 on the drum, I 35 prefer to omit one of the teeth of the rack, as indicated at 57.

In Figs. 1 and 2 the construction of the bed 2 and the arrangement of the parts in connection with the carriage are most clearly 40 shown. It will be observed that on its inner side the bed is provided with longitudinal horizontal guide-bars 26, and the aforesaid carriage 24 rests upon their upper faces and between the inner faces of the bed 2. These 45 bars 26 are provided at intervals along their length with inclined slots 27, through which screws 28 pass and secure them to the side of the bed.

It is desirable that the carriage should be 50 capable of a certain vertical adjustment, so that the position of the platen 25 may be that which is adapted for producing the best impressions of the type upon the sheet. For this purpose the aforesaid inclined slots 27 55 were provided. By means of adjusting-screws 29, mounted longitudinally in the ends of the bars 26 at the end of the bed, this adjustment of the carriage is effected. This construction is most clearly shown in Figs. 2 60 and 3. Check-nuts 30 prevent accidental displacement of the carriage after adjustment. Upon its lower side the carriage is

provided with small brackets or clips 31, which project so as to engage the lower face of the aforesaid guide-bars 26, so that the carriage 24 is held down upon the bed. A helical spring 32 operates to maintain the carriage normally in the extreme position, (shown in Fig. 2,) one end of this spring being secured to a bracket 58, carried by the bed. 75 It will be observed also from an inspection of this figure that the gear-teeth 22 do not extend completely around the periphery of the drum 7. Hence it will appear that after a certain amount of rotation of the drum has 80 taken place the rack 23 will pass out of engagement with these teeth, whereupon it will be returned to the normal and extreme position in which it is shown. The arrangement, however, is such that this return does 85 not take place until the carriage has passed sufficiently far beneath the drum 7 to take the impression of all the matter set up upon its face.

In order to prevent any ill effects which 90 might arise from the sudden or violent return of the carriage 24 by the spring 32, the dash-pot 33 is provided, preferably secured to the end of the bed 2, as indicated. It consists, substantially, of a horizontal cylinder 95 34, in which is mounted a loosely-fitting piston 35, the rod 36 of which projects horizontally and is adapted to abut the downwardly-projecting bracket 37, carried by the lower side of the carriage 24. A spring 38 operates 100 to force this piston outwardly to an extreme position when the table has passed to its outward position. By this arrangement the table is brought to rest quickly, but gently and easily, so that no jar is given to the 105 mechanism. It should now appear that if the handle 19 were continually rotated in one direction the drum 7 would be turned and the table would be made to pass beneath the drum in rapid succession, being always 110 returned by the spring 32 as soon as it becomes free of the gear-teeth 22. Hence if blank sheets be laid upon the platen one at a time they will receive printed matter as fast as the drum can be rotated. Means are provided for 115 removing each of these sheets after it has been impressed. This is preferably accomplished by means of a vacuum-cup 39, which is carried by an arm 40, as indicated. This arm 40 is itself carried upon the rock-shaft 41, 120 which passes across above the bed of the machine, being supported in brackets 42, secured to the sides of the bed. At one of its extremities, preferably the one which is on the same side as the rack, the rock-shaft 41 carries a 125 trip-lever 43, which inclines downwardly, as indicated, so that it may contact with a pin 44, which projects outwardly from the side of the rack 23. When this pin presses the lever upward, the vacuum-cup, which is 130 formed, preferably, of rubber, is depressed and forced downward upon the printed sheet lying upon the table. When the table commences to move back to its normal position,

the vacuum-cup prevents the return of the sheet of printed matter, and when the table passes from beneath it the vacuum is broken by air entering the cup around its edges.

5 The printed sheet falls upon the plate 45, which extends across the bed at this point, as indicated.

In order to provide for changing the time which the vacuum-cup is depressed, the rack 10 23 is provided with several holes 46 at different positions, all of which are adapted to receive the aforesaid pin 44. Proper alinement or register of the paper is effected by providing flat strips 47 48, which are arranged to 15 move in parallelism respectively with the longitudinal and transverse edges of the carriage. They are pivoted to the edge of the table on parallel arms 49.

Provision is made for feeding the band 21 20 automatically between the aforesaid spools 20. For this purpose, as clearly indicated in Figs. 2 and 8, the extremity of the spindle of each spool is provided with a gear-wheel 50, which lies at the end of the drum 7, and an 25 arm 51, which is pivoted to the drum at 52, carries a small pinion 53, the teeth of which are adapted to mesh with the teeth of either of the gears 50. This pinion 53 is rigid with a star-wheel 54, and if the arm 51 be set 30 cured in the position shown in Fig. 2 once in every revolution of the drum the star-wheel will come into contact with the pin 55, carried by the standard 4, and this operates to give the star-wheel a rotation, which is transmitted to the spools and effects an intermittent feeding of the band 21. If the arm 51 be set 35 given to the star-wheel the printing-drum is not in contact with the platen, and hence no resistance is offered to the movement of the band. A thumb-nut 120 affords means for locking the arm 51 in the positions described.

40 Proceeding now to a description of the mechanism for setting up the type in the channels of the printing-drum, it will be observed that the supply-drum 8, to which reference has already been made, is provided with channels 45 59, which are in all respects similar to the channels 12, formed upon the face of the printing-drum 7. In these channels are carried type arranged in rows according to the letters or characters which they represent, as will be 50 60 readily understood.

Referring especially to Figs. 1 and 4, it will appear that the upper extremity of the upright 3 is provided with a horizontal slot 60, which is of substantially the same depth and width as the channels of the two drums 7 and 8. By rotating the drums any channel of either drum may register with this slot. Hence

it will appear that if the printing-drum were held so that any particular slot or channel remained in register with this slot the supply-drum could be turned to successive positions, so that the different type-rows would be brought into alinement with the slot. Briefly, that is the way the type are set.

The inner ends of all the channels of the supply-drum are closed by a disk 61, which rests against the inner face 64 of the supply-drum in the manner indicated and is maintained against it by a helical spring 62, which thrusts against it around its center. This disk, however, does not turn with the supply-drum, and in order to enable the type to pass it it is provided with an opening 63, which alines with the aforesaid slot 60. The inner face of the supply-drum is provided with small openings 65, which are adapted to receive a small pin 66, which projects outwardly from the side of the upright standard 3. There are as many of these openings 65 as there are channels in the supply-drum, and when any channel of the supply-drum is in alinement with the aforesaid slot 60 an opening corresponding to this channel is then in alinement with the aforesaid pin 66. The extremity of this pin 66 is preferably conical or pointed, as shown at 67, and lies close to the face of the supply-drum, so that a slight movement of the supply-drum along the shaft 5 inwardly would operate to bring the pin and opening into engagement. From this arrangement it will be understood that when the supply-drum has been turned to bring a certain channel substantially into alinement with the slot 60 it is made to aline exactly with the slot by moving the supply-drum laterally along the shaft, so that the pin and recess engage in the manner which has been described. After this has taken place everything is in readiness to pass the matrix through the slot and into the channel of the printing-drum.

Mechanism is provided for utilizing the lateral movement of the supply-drum to effect the automatic passage of the matrix through the slot 60. For this purpose a movable pin 68 is mounted horizontally in the upright 3, and this pin has an enlarged head 69, which is received by an opening in the aforesaid disk 61 in the manner shown in Fig. 1. Its inner extremity is provided with a slot 70, through which passes an upright lever 71, attached to it by the pin 72. The lower extremity of the lever is pivoted to the upright 3 at 73, the upright being provided with a vertical recess 74 to receive it. Just above this lever 71 is mounted a rock-wheel 75, the lower side of which is provided with gear-teeth 76, which are adapted to mesh, as indicated, with gear-teeth 77, provided on the upper extremity of the aforesaid lever 71.

The upright 3 carries, as indicated, a horizontal feed-bar 78, which extends longitudinally of the machine above both the supply-drum and the printing-drum. One of its ex-

tremities rests upon the top of the standard 4, where it is secured by a strap 121. That portion of this bar which lies over the supply-drum supports a horizontal supply feed-rack 80, the lower edge of which is provided with teeth 81, which are shaped substantially as shown, and this feed-rack is provided with slots 82, which surround pins 83, carried by the aforesaid horizontal bar. As indicated 5 in Fig. 7, one extremity of these slots inclines downwardly, so that if the feed-rack were given an inward longitudinal movement with respect to the feed-bar it would be lowered and then advanced horizontally. When 10 this takes place, the teeth 81 engage with the upwardly-projecting teeth 84, which are integral with the chaser 85, carried in each of the channels of the supply-drum. These chasers are formed at their bases similarly 15 to the type, so that they are retained by the channels. As stated, one is provided behind the innermost matrix in each row, so that they can operate to force the entire row outwardly when the feed-rack is actuated. A 20 spring 86 normally constrains this feed-rack 80 in an extreme position, and an adjusting-screw 125, carried by it, is adapted to contact with the extremity of the feed-bar and limit the advance of the rack. In this manner the 25 amount of advance of the chaser 85 can be accurately determined beforehand, and it is needless to say the amount of this advance should be exactly the width of one matrix.

That portion of the feed-bar which lies 30 over the printing-drum is provided with a horizontal face 86, as indicated in Fig. 5, and upon this face rests a distributing feed-rack 87, which is in many respects similar to the supply feed-rack, which lies over the drum. 35 As indicated, however, the teeth 88 upon this feed-rack are upon its upper edge and inclined toward the supply-drum. The thickness of this rack is such that its upper face is flush with the face of the feed-bar, as indicated. Upon this feed-bar 78 and surrounding 40 the rack is mounted a rider 89, which is provided with a small block 90, having teeth on its lower face which project downward and incline in the opposite direction from those of the feed-rack. The construction of this rider 45 will be described more in detail later. Its function is to assist in bringing about the removal of the type from the channels of the printing-drum when they are being distributed back 50 upon the supply-drum. To this end the rack 87 is provided with pins 91, which project into a slot 92, formed in the feed-bar. These slots are inclined downwardly at one extremity in a manner similar to the slots in the feed-rack 55 over the supply-drum. Now if this feed-rack 87 were given a movement in the direction of the supply-drum the pins 91 which it carries would ride up in the slots 92 and elevate the rack, after which it would move on horizontally. 60 The rise of the rack is sufficient to bring about the engagement of its teeth with the teeth carried by the block 90 of the rider 65

and slides the rider along the feed-bar 78. Arrangements are made for limiting the amount of advance of this rider, as indicated at 93, 70 which arrangements are similar to those adopted at the opposite extremity of the feed-bar, and which have already been described.

At a point substantially near its middle the distributing feed-rack 87 is provided with a 75 recess 94, as clearly shown in Fig. 5, in which is mounted a small helical spring 95, which constrains the rack normally in an extreme position in which it is shown.

Proceeding now to a more detailed description of the rider and mechanism connected with it, and referring especially to Fig. 5, it will appear that this rider includes a yoke 96, surrounding the feed-bar, and having beneath the feed-rack an enlarged head 97, which head 80 is provided with a small vertical opening or bore 98. In the bore is mounted slidably a small bolt 99, provided with a laterally-projecting pin 100, which passes out through a vertical slot 101 in the head, as indicated. 85 This slot is further provided at its upper extremity with a lateral notch or recess 102, into which the aforesaid pin 100 may be moved, so that the bolt will be maintained in an elevated position. The pin affords means for 90 raising the bolt, as will be readily understood.

A chaser 103 lies in the channel just below the rider, and it is provided with a vertical bore 104 on the upper side which is adapted 100 to be engaged by the aforesaid bolt 99, wherefore movement of the rider can be transmitted to it, as indicated. The base of this chaser is constructed in a manner substantially similar to that of the type, so that it is retained 105 in the channels. Every channel of the printing-drum carries one of these chasers, and it may be well to say that they do not project from the drum as far as the face of the type, so that they do not operate to produce impressions through the inking-band.

Recurring again to the mechanism for automatically moving the rack for the purpose of effecting the feeding of the type, it will appear that the upright 3 is provided with an 115 upward extension or head 105, and an arbor 106 passes through this head and the aforesaid feed-bar 78. Upon this arbor is loosely mounted the aforesaid rock-wheel 75. As viewed in Fig. 4, the right-hand extremity of 120 this arbor 106 carries a short radial arm 108, which arm is provided with a laterally-projecting pin 109. This pin 109 is adapted to pass through a small elongated opening 110 in the inner extremity of the feed-rack, so 125 that its tip may be received by openings 111 112 in the aforesaid rock-wheel. In Fig. 1 this arm is shown so that it has pinned together the distributing feed-rack and the rock-wheel. Now evidently any movement 130 of the aforesaid lever 71 will be transmitted through the rock-wheel to the distributing-rack. Such a movement is brought about by the inner face 64 of the supply-drum imping-

ing with the head of the horizontal pin 68, and it will be remembered that the supply-drum is capable of this horizontal movement upon its shaft.

5 When the parts are connected in the manner shown in Fig. 1, the mechanism when actuated will of course operate to move all the type in the channels bodily toward the slot 60. It is needless to say that, as before, the 10 amount of movement is exactly one tooth-space and the same as the width of one type. A small helical spring 114 constrains the aforesaid arbor; but the same may be withdrawn by means of the head 115, and the pin 15 109 will be removed, so as to disconnect the distributing-rack 87 from the rock-wheel, whereupon the radially-projecting arm may be thrown to an opposite position, so that its pin may connect the feed-rack of the supply-drum with the rock-wheel 75. If such a 20 change were made, a movement of the lever 71, produced by the sliding of the supply-drum, would evidently then actuate the feed-rack of the supply-drum and effect an advance of type in one of its channels.

In order to hold the printing-drum in a fixed position in the manner described, the standard 3 is preferably provided with a second slot 116, in which is slidably mounted a 30 small lock 117. The dimensions of this second slot are substantially the same as those of the slot 60, and the distance between the two slots is the same as that between any two adjacent channels, so that when the slot 60 35 is in register with one of the channels of the printing-drum the slot 116 will then be in register with the adjacent channel. Evidently this lock 117 may secure the drum against movement.

40 The arrangement of the different characters or type carried by the supply-drum will be that which is best adapted for facilitating the operation of setting them up upon the printing-drum. It is found in practice, however, that this arrangement is preferably not in alphabetic sequence, for it is desirable to place those characters which are used with most frequency so that they can be brought into alinement with the slot 60 without being 45 obliged to turn the supply-drum through a great angle. For instance, channels with spaces or characters like the vowels "a" and "e" would be distributed with comparative frequency on the face of the supply-drum, 50 while channels occupied by letters which are not used frequently, as the letters "x" and "z," would of course not appear upon the face of the drum with the same frequency as the others. With such an arrangement the operation 55 of alining the channel carrying any particular character with the slot 60 is much facilitated, and in order that the operator may be able to tell at a glance what channel or character is alining with the slot a rim 118 is provided at the outer edge of the supply-drum 60 which carries letters upon it corresponding to the channel opposite which they are located.

As indicated in Fig. 1, this rim 118 has an annular portion 119, which closes all the outer ends of the channels of the drum.

70 From the foregoing description the operation of setting up the type upon the printing-drum and distributing them again into their proper channels upon the supply-drum should be clearly understood. However, it may be 75 said that in setting up the type on the printing-drum the band or transfer-ribbon which passes over the printing-face of the drum is first removed. This is done by winding the entire band upon one of the spools, and for 80 this purpose the extremity of the spindle may be squared, as indicated at 122, to engage with a key or crank. The printing-drum is then turned so as to bring that channel which is to carry the first line in alinement with the 85 slot, and it is locked in this position in the manner described. The supply-drum is then manipulated so as to bring any desired letter or character which it carries into alinement with the opposite end of the slot, whereupon 80 the automatic feeding mechanism having been properly connected the lateral sliding movement of the supply-drum effects an advance of one type-matrix into the slot. This operation continuing the type being set up 95 crowd each other back, the innermost member being in contact with the distributing-chaser. When a complete line has been set up in this way, the matrices which are then 100 lying in the slot 60 are pushed through by the hand of the operator with a pencil or similar pointed article, and the entire row is moved over against the closed extremity of the channel. When a line has been set up in this manner, the keeper 126, which is shown 105 in plan in Fig. 9, is placed in the slot behind the last type-matrix of the line. At their bases these keepers are constructed similar to the bases of the matrices, so that they run in the channels and are retained therein. 110 They are carried upon the supply-drum in the same manner as the regular type characters and type-spaces and are automatically fed from the supply-drum in the same manner. As will appear in Fig. 9, they are provided with a bifurcated extremity 123, and the bifurcations are resilient and tend outwardly, so that they will retain the follower in the channels against movement by a slight 115 force.

120 The length of the distributing-chaser is determined by the amount of margin desired at the left hand of the finished sheet. Where a greater margin is required for any particular line, this is obtained by utilizing the ordinary type-spaces, which are carried by the supply-drum, as stated.

The distance between the channels of the printing-drum is substantially the same as that between successive lines of type-written 130 matter, where the lines are printed as closely as possible. In ordinary work, however, only the alternate channels are set up with type, the intermediate channels being ignored.

With the mechanism described it is possible to set up and reproduce in large quantities and at a rapid rate the body or principal portions of circular letters or similar printed matter, after which the individual addresses required for each letter may be inserted by means of an ordinary type - writer having similar type characters to those used by the machine and a similar ribbon. In this manner a letter may be reproduced which has all the appearances of having been type-written, which is very desirable.

It should be understood that the bolt 99 in no way interferes with the rotation of the printing-drum, because, whenever necessary, it can be raised and locked in the elevated position, as described, where it will be out of danger of contact with the face of the drum.

What I claim is—

1. In combination, a rotatable drum, means for carrying type on the face thereof, a second member the surface whereof lies adjacent to the surface of said first member, means for moving said members relatively to each other, a transfer material, and means for passing the same between said members, substantially as described.

2. In combination, a rotatable member, means for carrying type upon the surface thereof, a second member, means for moving said members so that their surfaces may contact each other, a transfer material adapted to pass between said members, and means for automatically feeding said transfer material, substantially as set forth.

3. In combination, a rotatable drum, means for carrying type upon the surface thereof, a member coöperating therewith and having a surface adapted to be impressed by the surface of said drum, a band of transfer material carried by said drum, and automatic means for feeding said band, substantially as described.

4. In combination, a rotatable drum, means for holding type upon the surface thereof, a second member, means for moving said members so that their surfaces may contact, means for normally maintaining said second member in an extreme position, and a web of transfer material adapted to pass between said members, substantially as described.

5. In combination, a rotatable drum, means for holding type upon the face thereof, a second member, means for advancing said members so that their surfaces may impress each other, a band of transfer material adapted to pass between said members and automatic means for returning said second member to an extreme position, substantially as described.

6. In combination, a rotatable drum, means for retaining type upon the surface thereof, a second member, means for moving said members so that the surfaces thereof may impress each other, a band of transfer material lying between said surfaces, means for automatically feeding said band and means for

normally constraining said second member to an extreme position, substantially as described.

7. In combination a rotatable drum, means whereby said drum may carry type upon the face thereof, a member coöperating therewith, means for moving said members so that their surfaces may impress each other, a web of transfer material passing between the surfaces of said members, spools on said drum, carrying the ends of said band, and automatic means for feeding said band between said spools, substantially as described.

8. In combination, two coöperating movable members, means for driving one of said members, means for transmitting movement between said members, means whereby the surfaces of said members may impress each other, a transfer material passing between the said surfaces and means for disconnecting the said members to arrest said transmitted movement, substantially as described.

9. In combination, two coöperating movable members, means for driving the first of said members, means for transmitting the driving force therethrough to the second of said members, means whereby one of said members may carry type on the face thereof, means for disengaging said members, a transfer material adapted to pass between the surfaces of said members and automatic means for returning one of said members to an extreme position, substantially as described.

10. In combination, a rotatable drum, means for carrying type upon the face thereof, a movable carriage, means for moving said members so that the surface of said carriage may be impressed by the surface of said drum, means for returning said carriage to an extreme position, and a transfer material adapted to pass between said drum and said carriage, substantially as described.

11. In combination, movable members, the surfaces whereof may impress each other, means whereby one of said members may carry type on the surface thereof, means for moving said members so that said surfaces roll the one upon the other, a transfer material adapted to pass between said surfaces and means for adjusting the position of said members wherefore the degree of pressure between their surfaces may be regulated, substantially as described.

12. In combination, a rotatable drum, means for retaining type upon the surface thereof, a band of transfer material passing over said type, a carriage having an elastic platen, means for moving said members so that the surface of said drum may roll upon said platen, means for guiding said carriage and means for adjusting the position thereof with respect to said drum, substantially as described.

13. In combination, a rotatable drum adapted to carry type upon the face thereof, a band of transfer material adapted to cover the face of said type, a carriage having an elastic

5 platen, means for simultaneously moving said drum and said carriage so that said elastic platen may be impressed by the type upon said drum, a spring normally constraining said carriage to an extreme position and means for adjusting the plane in which said carriage moves, substantially as described.

10 14. In combination a rotatable drum adapted to carry type upon the face thereof, a transfer material adapted to cover the faces of said type, a movable carriage, means for driving said rotatable drum, means whereby said carriage may engage with said rotatable drum wherefore the former is advanced, means for 15 disengaging the connection between said drum and said carriage, and means for automatically returning said carriage to an extreme position, substantially as described.

20 15. In combination a rotatable drum adapted to carry type upon the face thereof, a transfer material adapted to cover the face of said type, a movable carriage adapted to pass adjacent to said drum, means for advancing said carriage so that the surface of said drum may 25 roll upon said carriage, automatic means for returning said carriage to an extreme position, and a dash-pot to cushion the return of the same, substantially as described.

30 16. In combination, a rotatable supply-drum, a rotatable printing-drum, means carried by said drums for holding rows of type, which may aline, one of said drums having a limited longitudinal movement, and means whereby said longitudinal movement may 35 aline said rows of type, substantially as described.

40 17. In combination, a rotatable supply-drum, a rotatable printing-drum, means whereby said drums may carry rows of type, one of said drums having a limited lateral movement, and means whereby said lateral movement may advance said type, substantially as described.

45 18. In combination, a rotatable drum, means carried thereby for retaining type in rows, a rotatable supply-drum axially alined therewith, said supply-drum having a limited lateral movement, and means whereby said lateral movement may aline the type-rows of 50 said supply-drum with those of said printing-drum, substantially as described.

55 19. In combination, a rotatable drum, a supply-drum, means carried thereby for retaining type, movable type, feeding mechanism for said type, said supply-drum having a limited lateral movement, means actuated thereby for alining said drums and actuating said feeding mechanism, substantially as described.

60 20. In combination, a rotatable drum, means for retaining type upon the face thereof, a supply-drum axially alining therewith and having substantially similar means adapted to retain a supply of type, said supply-drum having a limited longitudinal movement, and 65 means actuated by said longitudinal movement for advancing said type, substantially as described.

21. In combination, a rotatable printing-drum, a rotatable supply-drum mounted axially with respect to said printing-drum and 70 having a longitudinal movement, said drums having corresponding rows of type and means whereby said longitudinal movement may bring the said rows of type into alinement, and means actuated thereby for advancing 75 the type of said rows, substantially as described.

80 22. In combination, a member, means for carrying type upon the face thereof, a second member coöperating therewith and adapted to be impressed by the surface of said first member, a transfer material adapted to pass between said members and automatic means for feeding the type upon the face of said first member, substantially as described. 85

90 23. In combination, a member adapted to carry movable type upon the face thereof, a second member similarly adapted to carry type, means for moving said members so that said type may be alined, automatic means for feeding said type between said members, a third member, a surface whereof may be impressed by said first member and a transfer material adapted to pass therebetween, substantially as described. 95

100 24. In combination a rotatable printing-drum, a rotatable supply-drum, axially alined therewith, movable type carried by said drums and automatic means for feeding said type, substantially as described.

105 25. In combination, a rotatable printing-drum, a rotatable supply-drum, movable type carried by said drums, automatic means for feeding said type, a member adapted to be impressed by said printing-drum and a transfer material lying between said printing-drum and said member, substantially as described.

110 26. In combination a printing-drum, a rotatable supply-drum, movable type carried by said drums, means for feeding said type between said drums, a carriage coöperating with said printing-drum and adapted to receive blank sheets, and a transfer material passing between said printing-drum and said carriage, substantially as described. 115

115 27. In combination a rotatable printing-drum, a rotatable supply-drum, movable type carried by the faces of said drums, means for alining the type of one with the type of the other, said supply-drum having a limited lateral movement, means operated by said movement for feeding said type between said drums, a member coöperating with said printing-drum, the surface whereof is adapted to be impressed by the surface of said printing-drum and a transfer material adapted to pass between said member and said drum, substantially as described. 120

125 28. In combination a rotatable printing-drum, means for locking the same against movement, a rotatable supply-drum, said drums having means for carrying type upon their faces, means for indicating substantial alinement of the type-rows of said drums, said

- supply-drum being capable of a lateral movement and means whereby said movement may effect an accurate alinement of said channels, substantially as described.
5. 29. In combination, a rotatable printing-drum, means for locking the same against rotation, a rotatable supply-drum said drums being adapted to carry type in rows, means for indicating substantial alinement of the 10 type-rows of said drums, said supply-drum being capable of a limited lateral movement, means whereby said lateral movement may effect a complete alinement of said type-rows, and feeding mechanism adapted to move up 15 the type and actuated by the said lateral movement of said supply-drum, substantially as described.
30. In combination, a rotatable printing-drum, a rotatable supply-drum, said drums 20 having channels which may aline, said supply-drum having a limited movement along its axis, means for normally maintaining said drum in an extreme position, longitudinally-extending members lying above said channels and adapted to feed the type, and means 25 whereby the longitudinal movement of said supply-drum may actuate the same, substantially as described.
31. In combination, a rotatable supply-drum, a rotatable printing-drum, type carried 30 thereby, feeding mechanism adapted to advance said type, said feeding mechanism including a lever, said supply-drum having a limited lateral movement and means whereby 35 said lateral movement may actuate said lever, substantially as described.
32. In combination, a rotatable supply-drum, a rotatable printing-drum, type carried 40 thereby, feeding mechanism, a lever adapted to actuate the same, said supply-drum having a limited lateral movement, means whereby said lateral movement of said supply-drum may actuate said lever, and a spring normally 45 constraining said supply-drum toward an extreme position, substantially as described.
33. In combination, a printing-drum, a supply-drum, means for carrying type upon the faces of said drums, a rock-wheel, feed-racks 50 extending over said drums, movable type carried by said drums, means which may connect said racks with said rock-wheel and means for rotating said rock-wheel, substantially as described.
34. In combination a rotatable printing-drum, a rotatable supply-drum, type carried 55 in rows upon said drums, feed-racks extending over the alining type-rows of said drums, a rock-wheel, means for connecting said racks therewith and means for actuating said feed-racks by a movement of said supply-drum, substantially as described.
35. In combination a rotatable printing-drum, a rotatable supply-drum, feed-racks extending adjacent to the surface of said drums 60 and longitudinally thereof, said drums having type-rows, means for bringing said type-rows into alinement substantially beneath said feed-racks, a movable member, means for connecting said movable member with the inner extremity of either of said feed-racks 70 and automatic means for actuating said movable member, substantially as described.
36. In combination, a rotatable printing-drum, a rotatable supply-drum, feed-racks supported thereabove, type carried in longitudinal rows upon said drums, means for bringing 75 said type-rows into alinement substantially beneath said feed-racks, said feed-racks having a limited movement, means for constraining said feed-racks to an extreme position, means whereby said feed-racks may advance the type in said type-rows and automatic means for actuating said feed-racks, substantially as described.
37. In combination a member adapted to 80 have type set up thereupon, a member adapted to carry a supply of type, said type being carried in rows, means for bringing the type-rows of said members into alinement, racks extending over said alining rows, chasers behind said type adapted to engage said racks, automatic means for actuating said racks, and means for adjusting the movement thereof, substantially as set forth.
38. In combination a rotatable supply-drum, a rotatable printing-drum, rows of type 85 carried by said drums, which rows may aline, a fixed feed-bar extending substantially above said alining rows, feed-racks carried by said feed-bar and extending respectively over the 90 alining rows of said drums, a movable member, means for connecting the same so as to actuate either of said feed-racks and means whereby a lateral movement of said supply-drum may actuate said movable member, substantially as 95 described.
39. In combination a rotatable printing-drum, a rotatable supply-drum, members extending longitudinally of said drums and adjacent to the surfaces thereof, type carried in 100 rows on said drums, means for locking said drums so that rows thereof may aline substantially beneath said members, said members having a limited longitudinal movement, means whereby said movement may effect an 105 advance of said type, a rotatable member, means for connecting the inner extremities of said longitudinal members with said rotatable member and automatic means for actuating said movable member, substantially as 110 set forth.
40. In combination a rotatable printing-drum, a rotatable supply-drum, means for mounting type in rows upon said drums, chasers carried behind said type, means for 115 alining said rows of type and feeding mechanism adapted to advance said chasers, substantially as described.
41. In combination a rotatable printing-drum, a rotatable supply-drum, type carried 120 by said drums, in rows, chasers carried behind said type, feeding mechanism adapted to advance said chasers, and means whereby a lateral movement of said supply-drum may

- advance said feeding mechanism, substantially as described.
42. In combination, a rotatable supply-drum, means for carrying type thereon in rows, a member having substantially similar means adapted to receive set-up type, a second member between said first member and said supply-drum and normally adapted to prevent removal of type from said supply-drum, means for alining the type-rows of said first member with the type-rows of said supply-drum, said second member having an opening through which said type may pass, substantially as described.
43. In combination a supply-drum, a printing-drum, said drums being rotatable and having means adapted to retain type, a disk lying between said drums and adapted to prevent removal of said type, means for locking said disk against rotation, said disk having an opening therethrough, and means for alining the channels of said drums, substantially as described.
44. In combination, a rotatable supply-drum, a rotatable printing-drum, a disk abutting the inner face of said supply-drum, said disk having a recess in an edge thereof, said drums having channels which may aline therewith, the edge of said disk being adapted to close the inner ends of the channels of said supply-drum, substantially as described.
45. In combination a supply-drum, a printing-drum, a disk abutting the inner face of said supply-drum, means for locking said disk against rotation, said disk having a notch in an edge thereof through which type may pass, said drums having channels adapted to carry type and which may aline with said notch, and a spring constraining said disk against the face of said supply-drum, substantially as set forth.
46. In combination, a rotatable supply-drum, a printing-drum, said drums having channels adapted to carry type, means for locking said printing-drums in fixed positions, means for indicating a substantial alinement of channels of said drums, said supply-drum having a series of openings and a fixed member having a tapered point adapted to engage said openings, said supply-drum having a limited lateral movement which may effect said engagement, substantially as described.
47. In combination, a rotatable printing-drum, a rotatable supply-drum, a fixed member having a slot therethrough, said drums having channels which may aline with said slot, and adapted to carry type, substantially as described.
48. In combination, a rotatable printing-drum, a rotatable supply-drum, a fixed member therebetween, said fixed member having a slot therethrough adapted to pass type, and a lock mounted in said fixed member, said drums having longitudinal channels, said lock being adapted to engage with the channels of said printing-drum, substantially as described.
49. In combination, a rotatable printing-drum, type carried upon the face thereof, a band of transfer material carried by said drum and covering the faces of said type, a carriage coöperating with said drum and adapted to be impressed by said type, means for indicating the position of the blank sheet upon said carriage, a vacuum-cup and means carried by said carriage for automatically depressing the same upon said sheet after it has passed beneath said drum, substantially as described.
- In testimony whereof I affix my signature in presence of two witnesses.
- HARRY C. GAMMETER.
